OTHER PUBLICATIONS

U.S. Appl. No. 13/403764, filed Feb. 23, 2012, pending.
Design U.S. Appl. No. 29/416672, filed Mar. 26, 2012, pending.*Primary Examiner* — Mitchell Siegel(74) *Attorney, Agent, or Firm* — Knobbe Martens Olson & Bear LLP(57) **CLAIM**

The ornamental design for a golf club grip, as shown and described.

DESCRIPTION

FIG. 1 is a perspective view of a golf club grip embodying my new design;

FIG. 2 is a front view thereof.

FIG. 3 is a back view thereof.

FIG. 4 is a side view thereof.

FIG. 5 is a top view thereof; and,

FIG. 6 is a bottom view thereof.

Broken lines are used to illustrate features of the golf club grip that form no part of the claimed design.
